SEAL-LOCK.

1,269,248.

Specification of Letters Patent. Patented June 11, 1918.

Application filed June 27, 1916. Serial No. 106,174.

To all whom it may concern:

Be it known that we, LEON J. BAIRD and CHARLES G. LAY, citizens of the United States, and residents of Elmira, county of Chemung, State of New York, respectively, have invented certain new and useful Improvements in Seal-Locks, of which the following is a specification.

This invention relates to a seal lock and 10 more particularly to such a lock adapted for sealing freight cars.

The objects of the invention are to provide a lock which is held in locked position by means of a seal and can be opened only 15 by destroying the seal by the key actuated means; to provide a substantial lock which will indicate if it has been tampered with or opened, and one which can be manufactured at a very small cost.

20 These and other features of the invention will be described in connection with the drawings and pointed out in the appended claims.

In the drawings,

25 Figure 1 is a top plan view of the device;

Fig. 2 is a front elevation;

Fig. 3 is a bottom plan view;

Fig. 4 is a sectional view taken on the 30 line 4—4 of Fig. 1;

Fig. 5 is a sectional view taken on the line 5—5 of Fig. 4;

Fig. 6 is a sectional view taken on the line 6—6 of Fig. 4;

35 Fig. 7 is a sectional view of a detail taken on the line 7—7 of Fig. 4;

Fig. 8 is a sectional view of a detail taken on the line 8—8 of Fig. 4.

The device consists of a lock which is 40 adapted to be permanently attached to a car door by any suitable means and to be held in locked position by a seal which is inserted in the lock before it is closed and when the device is used on freight cars is 45 supplied to the various railroad stations preferably inscribed with the name of the station or a suitable number. In order to open the lock it is necessary to crush or break the seal. Hence an examination of the lock will immediately indicate whether the same has been opened or tampered with.

The seal lock comprises a casing A, the top of which is formed with two apertures 10 and 11 through which the legs 12 and 13 of a shackle 14 are adapted to extend.

The two legs of the shackle are of different lengths, the leg 12 being shorter than the leg 13, and adapted to project only a short distance into the casing. The other leg 13 which is the longer leg is slidably and rotatably mounted within the casing. By means of this mounting the shackle 14 may be slidably moved toward and away from the casing. Thus the shackle may be manipulated to pull it away from the position shown in Fig. 4 so that the end of the short leg 12 will be outside of the top of the casing and then the entire shackle may be rotated about the long leg as a pivot to a position as indicated in dotted lines 70 in Fig. 1. This is the unlocked or open position of the device. The top and bottom of the casing are formed with substantially elliptical openings 15 and 16 of such dimensions that a seal 57 may be 75 passed through the same. As clearly shown in the drawings these openings 15 and 16 are located adjacent the long leg of the shackle. A disk 17 is mounted on the long leg of the shackle and within the casing 80 and non-rotatively and slidably connected to the said leg in any suitable manner, as by means of the flat side indicated at 18. The leg 13 may slide relative to the disk, but the disk is held against all but rotative 85 movement by means of the guides or fingers 19 fastened to the casing. The disk is formed with an aperture 20 of the same dimensions as the aperture 15 and is so located on the long leg of the shackle that 90 when the shackle is in open or unlocked position the aperture 20 will register with the said opening 15, so that a seal may be inserted through the two openings. When the shackle is in closed or locked position, 95 however, the disk 17 will be rotated by the closing movement of the shackle 14 so that the aperture 15 will be closed by the same, thereby effectively preventing any tampering with the interior parts of the lock. At 100 the end of the long leg 13 and within the casing a sleeve 21 is connected to the same in a manner similar to the disk 17, and this sleeve carries at its lower end a flange or disk 22 similar to the disk 17. The disk 105 22 is formed with an opening 23 of substantially the same dimensions as the opening 16 and the sleeve is slidably and non-rotatively connected to the long leg 13 so that when the shackle is in open or un- 110

locked position the openings 23 and 16 register with each other, so that any seal that may be within the lock may drop through said registered openings. When the shackle 14 is in locked or closed position, however, the opening 16 is closed by the flange or disk 22 and the opening 23 is out of register with the opening 16 and of course closed by the bottom of the casing proper.

10 The sleeve 21 is connected to the leg 13 in any suitable manner as by means of a flattened side 24 on the leg and a corresponding flat surface on the sleeve.

A hollow cylindrical member 25 is adapted to be arranged within the casing in a transverse direction with respect to the length of the leg 13. At one end this cylindrical member abuts against the side of the casing, while at the other end it is cut away 20 as at 26 and the flap thus formed may be bent against the front of the casing as at 27 to form a support for a sleeve 28 and at the same time hold the cylindrical member in position. The cylindrical member may 25 be attached to the casing in any suitable manner, as by means of strips 29 and 30 fastened to the casing and to the cylindrical member. The aligned apertures 31 and 32 are formed in the cylindrical member and are 30 arranged so that a seal inserted through the opening in the top of the casing will pass downward through the said openings 31 and 32 in the cylindrical member. Between the top opening 31 and the top of the casing a 35 guide 33 is inserted of dimensions such that a seal may pass downward through the same. This guide is cut away at the top as at 34 and is formed with a longitudinal slot 35 substantially parallel with the long leg 13.

40 A deflector 36 is rigidly fastened to the long leg in any suitable manner so that it will occupy a position, as shown in Fig. 4 when the lock is in closed position. When the lock is in open position with the shackle with- 45 drawn the deflector will be in contact with the disk 17 and turned about the leg 13 to a position substantially at an angle of 90° with respect to the position shown in Fig. 7. When a seal is inserted through the opening 50 15 with the shackle in the open position it will pass into the guide 33; then when the shackle is rotated to bring the short leg 12 into position to be passed through the opening 10 the deflector 36 will be rotated also 55 through the opening 34 on the guide 33 into position to pass downward through said guide, and when the shackle is pushed downward or toward the casing the said deflector 36 will move downward through the guide 60 33 pushing the seal ahead of it. A similar guide 37 is mounted between the lower side of the cylindrical member and the bottom of the casing and in alignment with the openings 32 and 16 so that the seal will be guided 65 downward into position to pass through

the opening 16. Within the cylindrical member are mounted two plungers or slideable members 38 and 39. The member 38 is provided with a roller 40 and its movement in a direction away from the leg 13 is limited by any suitable means, such as an abutment 41 on the cylindrical member. A boss 42 is formed on the rear wall of the casing and the front wall is formed with a circular opening 43 through which is adapted to be inserted the sleeve 28. This sleeve is of such length that one end abuts the face of the boss 42 and the other end lies flush with the outside surface of the front of the casing. A pin 44 having a square end 45 is rigidly mounted within the sleeve 28 with one end projecting into a bearing recess 46 formed in the boss 42 and with the other end lying just within and protected by the end of the sleeve 28. A key is adapted to be inserted within the end of the sleeve 28 and to take over the end of the pin 44 whereby the sleeve 28 may be rotated when the key is turned. Two spaced apart spiders 47 are rigidly mounted on the sleeve 28 and each 90 of these spiders is shown as being formed with three arms. A pin 48 is mounted in each of the corresponding arms of the spiders and each pin carries a roller 49. The dimensions of the spider and the location of these rollers 49 is such that when the spiders are rotated by means of the key they will act against the roller 40 to move the slideable member or plunger 38 to the right, as shown in Fig. 4.

100 Within the slideable member or plunger 39 and carried by the long leg 13 is a sleeve 50 which is formed with a cam 51 of substantially circular outline but having a slabbed off or flat portion 52, adapted to contact with the flat surface of the head of the slideable member 39. This sleeve 50 is connected to the long leg 13 by means of a pin 60 projecting from the said leg and into a helically-shaped slot 53. By means of this pin and slot connection when the shackle 14 is moved outwardly from the casing the cam 51 will be rotated, and of course when the shackle 14 itself is rotated the said cam 51 will also move with it. The arrangement of the flat surface 52 and the plunger or slideable members 38 and 39 is such that when the shackle 14 is in closed or locked position the flat surface 52 contacts with the flat surface of the head of the slideable member 39 and the heads of the plungers or slideable members 38 and 39 are spaced apart just sufficiently to tightly and snugly receive therebetween a seal 57. It will be apparent that when such a seal is located between the two plungers 115 that sliding movement of the member 39 will be prevented, and consequently shackle 14 cannot be pulled outward or to open position because the flat surface 52 locks the said shackle against such sliding movement.

100

130

The seals 57 are made from two concaved disks 54 and 55 of sheet material, and these disks are fastened together by any suitable means so that the edges are in abutting relation. The material and formation of the seals are such that the seal will have sufficient strength to resist the force exerted on the same by any outward pull that may be exerted on the shackle 14, but may be crushed or broken by turning the key which will move the plunger 38 to crush or break the same.

In the operation of the device with the shackle 14 in the dotted or open position shown in Fig. 1, a seal is inserted through the openings 15 and 20 and into the guide 33. The shackle 14 is then rotated which will bring the deflector 36 into register with the guide 33. The shackle 14 is then pushed inward, the deflector 36 thus acting on the seal to push it downward and between the two plungers 38 and 39. The fit of the seal between these two plungers is sufficiently tight so that the seal will be held frictionally in position between the two thus the lock is held in closed or locked position. In order to open the same it is necessary to crush or break or destroy the seal 57 by turning the spiders 47 so that a roller 49 will act to move the plunger 38 toward the plunger 39. When the seal is crushed or broken by this key actuated means the shackle 14 may be opened, and the seal 57 will drop downward into the guide 37. When the shackle is moved into the dotted line position of Fig. 1 the openings 16 and 23 will be in register and the said broken or crushed seal may be discharged through the same.

Thus it will be apparent that a seal lock is provided in which the seal when inserted in the same prevents the lock from being opened and that in order to open the lock by the key actuated means it is necessary to crush or break or destroy the seal. Consequently if the lock has been tampered with or opened it will be immediately apparent on examination, because if tampered with or opened there will be no seal discharged from the lock or a mutilated one will be found within the same.

Having described the invention what is claimed is:

1. A seal lock comprising a casing, aligned openings in the top and bottom adapted to receive and discharge a seal, a shackle having legs of unequal length, the long leg extending through the top and pivotally and slidably mounted within said casing, a cylindrical member fastened in the casing, two opposed plungers slidable in said member, openings in the cylinder member walls in line with the openings in the top and bottom of the casing, a fixed abutment limiting movement of one of the plungers in one direction, key actuated means adapted

to slide said last mentioned plunger away from the abutment and toward the other plunger, a sleeve mounted on the said long leg of the shackle and having a flat sided cam adapted to form an abutment for the other plunger to hold it in spaced relation to the first mentioned plunger, the said openings and space between the plungers adapted to receive a disk seal, said sleeve and leg being connected by a pin and co-operating helical groove, the parts being arranged so that a seal between the two plungers prevents outward or unlocking movement of the long leg of the shackle.

2. A seal lock comprising a casing, a shackle having a long and a short leg, the short leg adapted to be inserted in an opening in the top of the casing, the long leg pivotally and slidably mounted in the casing, a member adapted to be moved by the sliding movement of the long leg in one direction, and means in the casing to receive a destructible seal in position to prevent the movement of said member and thereby the long leg of the shackle.

3. A seal lock comprising a casing, a shackle having a leg slidably mounted in the casing so that the shackle may be moved inwardly and outwardly with respect to the casing, a member within the casing, means for moving said member actuated when the shackle is pulled outwardly with respect to the casing, and means in the casing to receive a destructible seal in position to prevent the movement of said member.

4. A seal lock comprising a casing, a shackle mounted in the casing for sliding movement inwardly and outwardly with respect to the casing, a member within the casing, means for moving said member actuated when the shackle is pulled outwardly, means in the casing to receive a destructible seal in position to prevent the movement of said member, and key actuated means for destroying the seal to thereby free the shackle.

5. A seal lock comprising a casing, a member within the casing, a movably mounted shackle, means for moving said member actuated by outward movement of the shackle, a second member spaced from the first member and having limited movement in the direction away from the first member, means for inserting a destructible seal between said members and key actuated means for destroying the seal to thereby free the shackle.

6. A seal lock comprising a casing, a member within the casing, a movably mounted shackle, means for moving said member actuated by outward movement of the shackle, a second member spaced from the first member and having limited movement in the direction away from the first member, means for inserting a destructible seal

- between said members and key actuated means for moving one member toward the other to destroy the seal and thereby free the shackle.
- 5 7. A seal lock comprising a casing, a movably mounted shackle, a member mounted in the casing for sliding movement at an angle to the movement of the shackle, means for moving said member actuated by outward movement of the shackle, and means within the casing to receive a destructible seal in position to prevent the movement of said member.
- 10 8. A seal lock having means to receive a destructible seal to prevent opening of the lock, and key actuated means within the casing for destroying the seal to thereby free the lock.
- 15 9. A seal lock comprising a casing, a movably mounted shackle, a member slidably mounted in the casing, means connecting said shackle and member whereby outward movement of the shackle slides the member in one direction and means within the cas-

ing to receive a destructible seal in position to prevent movement of said member.

10 10. A seal lock comprising a casing, a movably mounted shackle, a member slidably mounted in the casing, cam means connecting said shackle and member whereby outward movement of the shackle slides the member in one direction and means within the casing to receive a destructible seal in position to prevent movement of said member.

30 11. A seal lock comprising a casing formed with an opening for the insertion of a destructible seal and having means therein to receive said seal, means actuated by closing the lock for closing said opening, and means also actuated by closing the lock for positively moving a seal into operative position in the first mentioned means.

35 In testimony whereof we affix our signatures.
